UNITED STATES PATENT OFFICE.

WILLIS M. FLEMING, OF HOLYOKE, MASSACHUSETTS, ASSIGNOR TO WORTHINGTON PUMP AND MACHINERY CORPORATION, OF NEW YORK, N. Y., A CORPORATION OF VIRGINIA.

PUMP.

Application filed August 10, 1921. Serial No. 491,108.

To all whom it may concern:

Be it known that I, WILLIS M. FLEMING, a citizen of the United States, residing at Holyoke, county of Hampden, and State of Massachusetts, have invented certain new and useful Improvements in Pumps, fully described and represented in the following specification and the accompanying drawings, forming a part of the same.

10 This invention relates to improvements in pumps.

It is an object of the present invention to provide a novel priming means especially adapted for pumps of that class in which delivery is effected by pump plunger displacement of liquid in a valved plunger chamber, and to so form and locate such priming means that it will co-operate with the suction air chamber to automatically supply air at all times, except during the priming operation, in sufficient quantity to insure satisfactory operation of the pump.

For a full understanding of the invention, a detailed description of a preferred embodiment thereof will now be given in connection with the accompanying drawings, and the novel features thereof then be specifically pointed out in the claims.

In the drawings—

30 Figure 1 is a partial vertical central section longitudinally of the pump plunger, and

35 Figure 2 is a view similar to Fig. 1, of the priming means, but showing the parts enlarged for clarity.

Referring now to the drawings, and particularly to Fig. 1, the pump construction consists of the usual cylinder casting A, pump plunger B, suction and discharge 40 valves, C, D, respectively, discharge air chamber E and pulsation chamber F. The crosshead G works in a guide 10 and is driven by any well known means, such, for example, as an eccentric connection to the 45 main shaft (not shown).

Referring now to Fig. 2, the means for priming the pump and also for supplying air in sufficient quantity at all times during the operation of the pump, except during 50 the priming operation, consist of a receptacle or basin 1 located adjacent to the pump cylinder, such basin having an opening 2 in the bottom thereof normally closed by a plug 3, which may be a screw plug, as shown. 55 The opening 2, when the plug 3 is removed,

is in communication with an extension 4 of the plunger chamber F, such chamber preferably being formed as shown, that is, with a flat top for elimination of air pockets, and an inclined bottom to facilitate flow of priming liquid. The suction air chamber H is in communication with the atmosphere through passage 5 and air snifting nozzle 6, connecting the priming basin 1 and passage 5, such nozzle being adapted to automatically admit air to the pump for the proper supply of the suction and discharge air chambers at all times except during the priming operation, as hereinafter explained. The end of the passage 5 is conveniently closed by a screw plug 7, and is also provided with an emergency cock 8. The snifting nozzle 6 is preferably formed of bronze and, as it is impracticable to drill a hole sufficiently small therein for the present purpose, such nozzle 75 is preferably provided with a tip formed of aluminum or some other non-corrosive metal, indicated at 9, which is set into the nozzle 6 in any suitable manner. The nozzle tip 9 is conveniently formed by first drilling a small hole, say, one-sixteenth of an inch in diameter, therethrough and then closing the end in over a piece of steel wire of the proper diameter, the latter being subsequently withdrawn. A very small hole of 80 the proper size can thus be properly and rapidly formed, and is particularly well adapted for the present use, in that the nozzle tip or opening being at the extreme end, there is little chance for paint or grease to 85 pack around the opening, as would be the case if such opening were in a recess. This feature renders the nozzle tip practically selfcleaning.

The operation of the priming means above described is as follows: Plug 3 in priming basin 1 having been removed and the cock 8 being closed, priming liquid is supplied to such basin until the pulsation chamber F is filled and the liquid in the basin covers the 95 nozzle tip 9, thus preventing access of air to the suction air chamber through nozzle 6 and passage 5. The plug 3 is then replaced in opening 2 and the pump started. In the 100 continued operation of the pump, the liquid in the priming basin 1 will be gradually drawn into the pump cylinder until the level thereof in such basin has reached and exposed the orifice in the nozzle tip 9 to the 105 atmosphere, when air will be admitted to 110

the suction air chamber and the pump then take up automatically its air charging function, until stopped and priming is again necessary, when the operation above described will be repeated.

It will be understood that various modifications may be made in the features of construction above described and still be within the scope of the claims, and it will also be understood that the invention is not to be confined to use solely with pumps of the class herein shown and described, but may be applied to various other pump constructions and also in other relations with equal advantage.

What is claimed is:

1. Priming means for pumps and the like, comprising a liquid receiving receptacle having an opening for admitting liquid to the pump cylinder, means for closing said opening, and an air supplying connection with said receptacle adapted to be sealed by the liquid therein during the priming operation.

2. Priming means for pumps and the like, comprising a liquid receiving receptacle having an opening for admitting liquid to the pump cylinder, means for closing said opening, and a suction air chamber connection with said receptacle adapted to be sealed by the liquid therein during the priming operation.

3. Priming means for pumps and the like, comprising a liquid receiving receptacle having an opening for admitting liquid to the pump cylinder, means for closing said opening, and an air supplying connection with said receptacle adapted to automatically admit air to the apparatus on completion of the priming operation.

4. Priming means for pumps and the like, comprising a liquid receiving receptacle having an opening for admitting liquid to the pump cylinder, means for closing said opening, and an air snifiting nozzle connected with said receptacle and adapted to automatically admit air to the apparatus when the liquid level in said receptacle exposes the nozzle orifice to the atmosphere.

5. Priming means for pumps and the like, comprising a liquid receiving receptacle having an opening for admitting liquid to the

pump cylinder, means for closing said opening, and an air snifiting nozzle connected with said receptacle and adapted to automatically admit air to the suction air chamber of the pump when the liquid level in said receptacle exposes the nozzle orifice to the atmosphere.

6. Priming means for pumps and the like, comprising a priming basin communicating with the pump cylinder, means for closing communication between said basin and cylinder, and an air snifiting nozzle connected with said basin and adapted to admit air to the suction air chamber during normal operation and to automatically shut off said air supply during priming.

7. Priming means for pumps and the like, comprising a priming basin having an opening for admitting liquid to the pump cylinder, a removable plug for closing said opening, and an air snifiting nozzle connected with said basin, said snifiting nozzle being adapted to prevent entrance of air to the suction air chamber of the pump during priming but to automatically admit air thereto when sufficient liquid in said basin has been withdrawn through said nozzle to expose the orifice thereof to the atmosphere.

8. Priming means for pumps and the like, comprising priming basin 1 communicating with the pump cylinder, and nozzle 6 for supplying air to suction air chamber H, the air inlet of nozzle 6 being within and above the bottom of the basin.

9. A priming means for pumps and the like, comprising priming basin 1 communicating with pulsation chamber F, plug 3, and snifiting nozzle 6 having tip 9 for conveying air to suction air chamber H after the priming operation, the air inlet of nozzle 6 being within and above the bottom of the basin.

10. The combination with priming means for pumps and the like, of air snifiting nozzle 6 having removable tip 9, the orifice in said tip being closed in at the end of the tip to reduce the diameter of the tip bore.

In testimony whereof, I have hereunto set my hand.

WILLS M. FLEMING.
